[57] CLAIM

The ornamental design for a multiple slide holder for use in a photographic scanner, as shown and described.

DESCRIPTION

FIG. 1 is a top perspective view of a multiple slide holder for use in a photographic scanner, showing my new ornamental design;

FIG. 2 is an enlarged top elevational view thereof;

FIG. 3 is an enlarged bottom elevational view thereof;

FIG. 4 is an enlarged right side elevational view, the undisclosed left side view being a mirror image thereof;

FIG. 5 is an enlarged front elevational view thereof;

FIG. 6 is an enlarged rear elevational view thereof; and,

FIG. 7 is a perspective view of the open slide holder.
